COLLET OR SHELL DIE FOR BUTTON MAKING.

No. 374,741.

Patented Dec. 13, 1887.

UNITED STATES PATENT OFFICE.

WILLIAM HORNICH, OF NEWARK, NEW JERSEY.

COLLET OR SHELL DIE FOR BUTTON-MAKING.

SPECIFICATION forming part of Letters Patent No. 374,741, dated December 13, 1887.

Application filed April 11, 1887. Serial No. 234,325. (No model.)

To all whom it may concern:

Be it known that I, WILLIAM HORNICH, a citizen of the United States, residing at Newark, in the county of Essex and State of New Jersey, have invented certain new and useful Improvements in Collet or Shell Dies for Button-Making; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to reduce the labor and expense of manufacturing that class of buttons used particularly for men's pants, having sheet-metal shells or back-plates, in which the name of the manufacturer, or the 20 trade-mark, or other lettering or inscriptions are impressed. Heretofore in dies for striking out the said shells or sheet-metal backs prior to securing them in the button one die provided means for striking out and forming the 25 shells, and another independent die provided means for impressing the wording or inscriptions above referred to, two independent processes being thus required and a consequent loss of time and labor. In the improvement 30 means are provided for striking out the blank, centrally perforating and turning the outer edges of the same, and with the same stroke of the device impressing the lettering into the face of the sheet metal.

35 The invention consists in the improved die, and in the combination and arrangements of parts thereof, substantially as will be herein-after set forth, and finally be embodied in the clauses of the claims.

40 Referring to the accompanying drawings, in which like letters indicate corresponding parts in each of the several figures, Figure 1, Sheet 1, is a front elevation of an ordinary frame or bed carrying the improved die-sections. Fig. 45 2 is a plan. Fig. 3 is a side elevation, and Fig. 4 is a sectional view, of a portion of a die-section in detail. Fig. 5 is an enlarged side elevation of the co-operating sections in detail, and Fig. 9 is a reduced sectional view of the 50 same, taken through line y. Figs. 6, 7, and

8 are detail views of certain parts, which will be duly explained.

In said drawings, a is a frame or bed, and b a plunger having a vertical reciprocating movement in ways c c therein, under the influence of a suitable driving wheel, d, and eccentric e, in any ordinary manner. Upon said plunger or its equivalent is secured, by screwing or other mode of attachment, the upper or male-die section, f, and to the lower portion 55 of the frame or upon the table or bed thereunder is secured the lower or female-die section, g. Of said male section, h is a hollow head provided with a threaded shank, h', by means of which it is secured to the plunger, 60 and having secured or joined therein a perforator, i, which extends centrally through the chamber h² therein and through a chamber, j, Fig. 4, of a blank-cutter head, h³, and at its lower extremity lies about flush with the lower 65 end of the said blank-cutter head.

The blank-cutter head h³ (shown in detail in Figs. 2, 3, and 4) is secured to the head h by means of the set-screw m, or other suitable device, and at its lower and outer edge, as at l, 70 is provided with a cutter, which on the descent of the plunger first engages the co-operating edge l' of the female-die section, cutting the blank, and then entering said female section, as will be understood upon reference to Fig. 9, 75 80

The lower end of the head h³ is countersunk after the manner illustrated in Fig. 4 at l', forming the cutter l, above referred to, and also an impression-surface, l'', in which the letters to be transferred or reproduced in or 85 on the face of the sheet-metal shell are found.

The perforator i, extending through the chamber or opening j, is enveloped by a "stripper" or sleeve, n, which moves longitudinally on the perforator, so that when the shell-blank 90 is struck out, its edge turned, the center perforated, and the face impressed, and the male die moves away from the female, carrying the shell with it, the said shell may be forced from the male die by means of the said stripper, being forced downward against the upper side of the shell by hand power or automatically. The stripper is preferably operated by means of finger-pieces o o, which are carried on a ring, o', and extend through slots p in the 95 100

head h and engage the head n' of the stripper. The ends of the finger-pieces preferably extend into a recess, o' , Fig. 6, in said head. By this construction it will be observed that the stripper 5 per may have a movement of the length of the slot, and that it is prevented from dropping from its proper relation to the die.

The female portion g of the die provides a cutting-edge, l' , to co-operate with the cutter 10 l for striking out the blank, a chamber, s , into which the edges of the blank are forced to form the shell, a head, t , projecting upwardly through said chamber, the upper edge of which is provided with sunken letters to co-operate 15 with the raised letters on the head h of the male die and form the inscription in the shell, and a central aperture, u , in said head t to receive and co-operate with the perforator in striking out the center of the shell to form the 20 perforation therein. As the male die descends, the end of the stripper rests on the head t , and is allowed to stand stationary therein while the die continues its descent. When the male die again ascends from the female, it carries 25 the finished shell with it, which is then removed by forcing the stripper downward with the hand.

I am aware that changes may be made—such, for example, as transposing the parts from the 30 male to the female, and vice versa—without effecting the scope of the invention; and I do

not wish to be limited to any exact arrangement shown or positively described.

What I claim as new is—

1. In combination, in a machine for making 35 collets or shells for buttons, a die section comprising a perforator, i , a stripper, and a head, h , having a cutting-edge, l , and impression-surface t' , and a co-operating die-section having a cutter, l' , and apertured head t , with an 40 impression-surface to co-operate with that of the first said die-section, substantially as and for the purposes set forth.

2. In combination, in a machine for making 45 collets or shells for buttons, a die-section comprising a hollow head, h , a perforator, i , and a sleeve, n , around said perforator for stripping the shell from the die, finger-pieces for operating said stripper, a head, n' , secured upon said head h , and having a countersunk extremity forming a cutter, l , and a lettered impression-surface, and a co-operating die-section having an apertured head, t , with a chamber, s , therearound, and a cutter, l' , substantially 50 as set forth.

In testimony that I claim the foregoing I have hereunto set my hand this 29th day of March, 1887.

WILLIAM HORNICH.

Witnesses:

CHARLES H. PELL,
OSCAR A. MICHEL.
